UNITED STATES PATENT OFFICE.

JOHN G. NATTINGER, OF CHICAGO, ILLINOIS.

CARRIAGE-RETURN MECHANISM FOR TYPE-WRITERS.

1,140,182.

Specification of Letters Patent.

Patented May 18, 1915.

Application filed February 3, 1913. Serial No. 745,762.

To all whom it may concern:

Be it known that I, JOHN G. NATTINGER, a citizen of the United States, and a resident of the city of Chicago, in the county 5 of Cook and State of Illinois, have invented certain new and useful Improvements in Carriage-Return Mechanism for Type-Writers; and I do hereby declare that the following is a full, clear, and exact description 10 of the same, reference being had to the accompanying drawings, and to the numbers of reference marked thereon, which form a part of this specification.

Many attempts have been made to construct a shifting mechanism for the platen and carriage of a type-writer whereby the same might be actuated by the foot of the operator, but in most cases such attachments have not proved adaptable to various makes 20 of machines and they have embodied such complicated constructions as not to permit the same to come into general use. In the prior constructions of this nature, due attention has not been given to the actuating 25 mechanism for the shifting means and for this reason the devices have not proved a success.

It is an object of this invention to provide an attachment for typewriters whereby 30 the platen may be rotated and the carriage shifted by means actuated by the foot of the operator, and not necessitating any adjustment requiring the use of the hands of the operator.

35 It is a further object of this invention to provide a device which may be attached to practically any make of typewriter.

It is also an object of this invention to provide means whereby the device may be 40 attached or detached from the machine without alteration or adjustment of any of the parts of the machine.

It is also an object of this invention to provide means whereby the carriage may 45 be shifted any desired distance within the prescribed limit allowed by the machine.

It is also an object of this invention to provide a signal locking means for the actuating mechanism, thus insuring the complete 50 return of said mechanism to initial position after each shifting operation thereof.

It is also an object of this invention to provide yielding means between the shifting mechanism for the typewriter and the actuating means therefor.

The invention is adaptable for many other similar purposes and (in its preferred form) consists in the matters hereinafter more fully described and defined in the appended claims.

60

In the drawings: Figure 1 is a front elevation of a device embodying my invention, shown connected to a typewriter. Fig. 2 is a top plan view of the typewriter, showing the bracket and cable connected thereto. Fig. 3 is a side elevation of a device embodying my invention connected to a typewriter, showing the relative position of the parts. Fig. 4 is an enlarged detail of the foot actuated means. Fig. 5 is a top plan view thereof. Fig. 6 is a fragmentary detail of the bracket shown clamped on the typewriter frame. Fig. 7 is a fragmentary top plan view of the typewriter mechanism, illustrating the usual relation of the parts 75 of the shifting mechanism. Fig. 8 is an enlarged view of one of the sheaves, showing a cable guard attached thereto.

As shown in the drawings, the typewriter as a whole, is indicated by the reference 80 numeral 1, and clamped upon one side of the base frame thereof, is the bracket 2, the lower end of which is flanged over, as shown at 3, to coact with the other clamping member 4, to engage the frame member 5, 85 of the typewriter. A bolt 6, affords an adjustable connection between the clamping jaws 3 and 4. Said bracket 2, is twisted through an angle of substantially 90 degrees, as shown at 7, and is inclined rearwardly 90 and outwardly to extend to a point substantially at the limit of, and in alignment with the travel of the platen carriage of the typewriter.

8, indicates the usual rotatable platen of 95 a typewriter, which is provided at one end thereof with a ratchet wheel 9, adapted to be engaged by the pawl 10, pivoted on an extension of the member 11, said pawl actuating to rotate the platen through the desired 100 amount required for the line spacing.

Journalized at one end of the carriage frame 12, is the actuating shaft 13, which is rigidly connected to the member 11, and also to the element 14, provided with the extending arm 15. Said shaft 13, is provided with a lever 16, adapted for manual engagement by the operator. A spiral spring 17, is wound about said member 11, and is adapted to hold the same, together with the 110

arm 15, and lever 16, in retracted position with the pawl 10, and ratchet 9, out of engagement.

Mounted upon the floor, or in any position convenient for operation by the foot of the operator, is the frame member 18, having journaled therein a bell crank comprising the arms 19 and 20 respectively. Pivotedly connected at the lower end of the arm 20, of said bell crank, is the foot rest or pedal 21, as shown provided with an offset 22, to receive the heel of the shoe of the operator. Projecting upwardly from the frame 18, is the inclined lug 23, adapted to form a stop for the arm 20, of the bell crank when in initial position and also to engage behind the heel portion 22, of the foot pedal to retain the bell crank in said initial position. Said frame member 18, is provided with holes 24, to receive means for attaching the same to a suitable support. Means are provided on the frame member 18, for limiting the throw of the bell crank, comprising a slotted plate 25, adjustably engaged on the frame member 18, by means of the screws 26. Said slotted plate is provided with a flange 27, adapted to be contacted by the arm 20, to afford a stop for said crank. Engaged in an aperture in the bell crank 30 arm 19, is the spiral tension spring 28.

Secured to the end of the spring 28, is a cable 29, which is led upwardly and trained around the respective sheaves 30 and 31, mounted on the bracket 2. Said 35 sheaves are inclined at such an angle as to permit the cable to be freely led from the lower end of the bracket 2, upwardly and around the extended end of the same and thence parallel the typewriter carriage to 40 the actuating arm 15, to which the cable is secured. By such disposition of the cable, the same is accessible for convenient adjustment by the operator and at the same time is removed from possible interference during the normal operation of the typewriter.

As shown in Fig. 8, mounted on the stud shaft for each of the sheaves 30 and 31 respectively, is a guard member 32, adapted to retain the cable 29, on the sheaves when 50 the same becomes slack.

The operation is as follows: The applicant's device is suitable for attachment to any make of typewriter, it only being necessary to connect the cable 29, directly to the 55 actuating lever for the platen and carriage or to a conveniently disposed lever for the purpose, as shown in this case as 15. The slotted plate 25, is then adjusted to a position whereby the throw of the bell crank 60 will be limited to an extent depending upon the amplitude of movement of the carriage, as desired. Assuming the platen and carriage to be in the central position, as shown in Fig. 1, a certain amount of slack in the 65 cable 29, will exist between the sheave 30,

and the spring 29, which, as the platen and carriage move to the left, will be taken up until such movement is arrested, such a position being indicated by the right hand margin of the paper, which is being used in 70 the typewriter. When in such a left hand extreme position, the bell crank is in the position shown in Fig. 4, and the operator then shifts his foot slightly forward, thus releasing the offset 22, from the lug 23, 75 and at the same time thrusts the crank 20, forwardly to the limit imposed by the projecting flange 27, and then with his foot still on the pedal, allows the lever 20, to swing back to initial position, the lug 23, 80 and offset 22, acting automatically to lock the same therein. It will thus be seen that a sensible signal is afforded the operator whereby he becomes aware that the mechanism has moved through the entire amplitude of movement necessary and thus precludes any accidental and annoying stoppage of the typewriter carriage, intermediate the extreme position, if sufficient slack is not present in the cable, due to the incomplete movement of the operating mechanism. Another novel feature of great utility in the applicant's invention is the inclusion of the spring 28.

It is readily seen that in the rapid manipulation of a typewriter, and the operating mechanism therefor, that if the momentum of the foot operated means were transmitted directly to the carriage of the typewriter, as the same reached its extreme position, the resultant increase in the energy of impact would soon prove disastrous to the machine. This is obviated by the inclusion of the spring 28, which affords a yieldable connection between the actuating mechanism 105 and the carriage of the typewriter.

Of course, it is to be understood that details of the construction may be modified, and I do not purpose limiting the patent granted, otherwise than necessitated by the prior art.

I claim as my invention:

1. In a device of the class described a bracket adapted to be releasably secured to the frame of a typewriter and projecting upwardly and outwardly therefrom at an angle therewith, sheaves journaled on said bracket, a cable connected at one of its ends to the actuating lever of a typewriter carriage and trained about said sheaves on said bracket, a pivotally mounted bell crank having the other end of said cable yieldably connected thereto, and a foot pedal pivoted on said bell crank.

2. In a device of the class described a cable connected to the actuating lever of a typewriter carriage, a bell crank, stops permitting an adjustable amplitude of movement therefor, and a spring connecting said cable and said bell crank.

3. In a device of the class described the combination with a typewriter and its carriage movable thereon, of a bracket rigidly secured to the frame of the typewriter near the front thereof and projecting at an angle outwardly and rearwardly to a point substantially in line with said carriage, sheaves journaled on said bracket, a cable trained about said sheaves and secured at one of its ends to the actuating lever of said typewriter carriage, a frame member adapted to rest on the floor beneath the typewriter, a bell crank pivotally mounted thereon, with one end of said cable yieldably connected to one arm of said bell crank, and foot actuating means connected to the other arm of said bell crank.

4. In a device of the class described the combination of a typewriter and its carriage movable thereon, of a bracket rigidly and releasably secured to the frame of the typewriter and projecting upwardly and rearwardly thereof to a point substantially in line with said carriage, sheaves journaled on said bracket, a cable trained about said sheaves and connected at one of its ends to the actuating lever of said typewriter carriage, a bell crank pivotally mounted beneath said typewriter, a foot pedal having an offset heel piece formed thereon pivotally mounted upon said bell crank, and with the other end of said cable connected also to said bell crank, an inclined lug mounted in

the path of movement of said foot pedal whereby said heel piece is elevated and engages thereover during a return movement of the bell crank to initial position, thereby affording a sensible signal to the operator by such elevation, of the complete return of the bell crank to initial position, and mechanism adjustable to limit the amplitude of movement of said bell crank.

5. In a device of the class described the combination with a typewriter, of foot actuated means for returning the carriage thereon to initial position, said means comprising in part a bell crank pivotally mounted and operatively connected to said carriage, a foot pedal pivotally mounted upon said bell crank to actuate the same, an offset heel piece formed on said foot pedal, and fixed means in the path of movement of said pedal adapted to coact with said offset heel piece to elevate the pedal, affording a sensible signal for the operator of the complete return movement of the bell crank and said heel piece then acting together with said fixed means to retain said bell crank in initial position.

In testimony whereof I have hereunto subscribed my name in the presence of two subscribing witnesses.
